PLUG FUSE

Ernst A. G. Ganoe, Rochester, Pa., assignor to
 National Electric Products Corporation, Pittsburgh, Pa., a corporation of Delaware

Application July 6, 1935, Serial No. 30,097

10 Claims. (Cl. 200—130)

This invention relates to plug fuses and contemplates an improved plug fuse structure particularly suited for present day commercial manufacture.

5 Plug fuses have been used for many years. The fuse is a plug structure having a cavity which contains a fuse link; there is a window through which the link can be observed; and the link is electrically connected to an exterior center contact and an exterior screw contact. In general, plug fuses have been made in two ways. One of the ways is by forming the body portion of the plug as an open topped cup of porcelain or "Bakelite", and closing the cap by a mica or 10 glass disc secured in place by a crimped metal band that embraces the top of the plug. This form of fuse body is simple in design, but the metal band is objectionable in that it must be grasped with the hand in inserting the fuse and involves a certain degree of hazard due to the electric conductivity of the band and sharp burrs which may occur on it. The other plug fuse construction that has been generally used involves an inverted glass cup which provides the 15 fuse link cavity and through which the fuse link can be observed. This construction requires a separate bottom piece of porcelain or "Bakelite" that has to be cemented or otherwise secured to the inverted glass cup. This involves obvious manufacturing disadvantages, and sometimes 20 results in a somewhat fragile fuse.

An object of the present invention is to provide a fuse plug having the advantages of the open topped cup body without the disadvantages that 25 have heretofore existed with such type of construction.

Another object of the present invention is to provide a sturdy, reliable fuse plug that meets the requirements of commercial manufacture 30 from the standpoint of cost, ease and rapidity of manufacture, accuracy, small percentage of bad fuses, etc.

Of course, plug fuses may be used in any position as far as up-side-down or right-side-up is 35 concerned, but for the sake of convenience, the drawing illustrates the fuse, and it will be described throughout, on the assumption that the axis of the plug is standing vertically with the window lying in a horizontal plane at the top 40 of the fuse.

Fig. I is a central vertical section of a complete plug fuse embodying the present invention.

Fig. II is a plan view with large portions of the top structure broken away to disclose the 45 interior of the plug.

Fig. III is a bottom view of the complete fuse. Fig. IV is a detailed sectional view taken on the line 4—4 of Fig. II.

Fig. V is a view of the closure retaining member of the fuse, part of the view being in central vertical section, and part of the view being in elevation.

Fig. VI is an elevation of the lower portion of the plug body.

In the original bristol board drawings filed in 10 the Patent Office all of the figures are on an enlarged scale, being much larger than the commercial fuse from which they were made. The particular fuse illustrated in the drawings is for use with a receptacle equipped with a circuit 15 breaking adapter, e. g. the receptacle shown in Moore Patent 1,990,953 issued February 12, 1935, but many of the advantageous features of the present construction may also be utilized in plug fuses designed for the standard Edison base 20 socket.

Referring to the drawing, the plug fuse is built up about a body portion designated as a whole by 1, which consists of a single piece of molded insulating material such as a suitable 25 phenol condensation product. The body 1 is cup-shaped, having an annular wall 2 which surrounds a cavity 3, and having a transverse portion 4 which forms the bottom of the cup-shaped formation. A skirt 6 depends from the bottom 30 of the cup formation and is molded with threads 7 on its exterior surface, as is more clearly shown in Fig. VI. The upper portion of the fuse body is formed with two concentric walls 8 and 9 separated by an annular space. The exterior 35 surface of the outer wall 9 is serrated at 9^a to form a hand grip for manipulating the fuse; and the interior surface of the wall 9 is annularly relieved or recessed at 9^b to receive a retainer which will be referred to later. While newly 40 molded phenol condensation product is still hot after being heated in the mold, it is somewhat elastic and this permits the body 1 to be stripped from the mold despite the annular recess 9^b.

A plurality of transverse radial notches 10 are 45 formed in the top of wall 8; and from the bottom of the annular space between walls 8 and 9, a plurality of apertures 11 extend downwardly to the exterior of the plug body. Molded into the body 1 is a channel 12 extending downwardly from the 50 top of wall 8 on the interior of the body, and aligned with the channel 12 is a second molded channel 13 which extends upwardly on the exterior of the body. These two channels intersect with one another sufficiently to provide a 55

narrow passageway from the cavity 3 to the exterior of the body. The bottom 4 of the cavity 3 is formed with an apertured depressed center portion 4^a, and in the wall of the aperture are 5 four vertical grooves 4^b. At their lower ends the vertical grooves 4^b intersect with horizontal grooves 4^c, that are on the bottom of body portion 4^a. On the top of body portion 4^a there are 10 radially extending grooves 4^d positioned between 10 vertical grooves 4^b.

A copper contact button 16 has a shank 17 which is initially tubular, like a tubular rivet. After the shank 17 has been inserted through the aperture of the body portion 4^a, portions of the 15 shank are stamped outwardly at 17^a into the horizontal channels 4^d, thus fixedly securing the contact button 16 in place. A fuse link 18 has one end soldered to the contact button 16 and passes downwardly to the exterior of the body 1 through 20 the aperture provided by the meeting of channels 12 and 13. If desired, suitable cement may be used at 18^a to seal the opening through which link 18 passes. A threaded metal ferrule 19 is screwed onto the threads 7 of the plug body, and the fuse 25 link 18 is soldered to this ferrule. A portion 19^a of the ferrule is struck into a notch 6^a on the plug body, thereby preventing unscrewing of the ferrule.

A closure disc 22 of suitable material such as 30 glass or mica is placed on top of wall 8, which acts as a means for supporting the closure disc. Then, a closure retainer, designated as a whole by 23 is applied on top of the closure disc 22 and secures it in place. This retainer 23 is a single 35 piece of springy sheet metal, having an inwardly extending annular flange 24 and a depending skirt 25 that is folded back upwardly at 25^a. The edge portion 25^a is flared outwardly, so that when the retainer is applied as shown in Fig. I 40 this edge engages in the annular recess 9^b and locks the retainer and the closure disc 22 in place. The skirt portion 25^a is usually a continuous annular metal band, but in the alternative, vertical slits such as 25^c may be provided to increase the 45 yielding range of the skirt if desired. The flange 24 inclines downwardly as it progresses inwardly; and the very edge portion 24^a of the flange may be additionally depressed if desired. When the 50 retainer is applied the edge portion 24^a strikes the closure disc 22 and yields upwardly, thus clamping the closure 22 under yielding spring pressure. This provides a degree of adjustment to take care of manufacturing variations in the 55 location of annular recess 9^b and the thickness of the glass or mica 22.

When the fuse blows, considerable hot gas is generated and this is vented through tortuous passages which cool the gas and prevent any danger of damage. From the cavity 3 gases may 60 pass downwardly through the vertical grooves 4^b and outwardly through connecting horizontal grooves 4^c. Also, gases pass through notches 10 to the annular space between walls 8 and 9, and out to the open air through downwardly extending 65 passageways 11. The edge of the retainer 23 may make a fairly tight fit with the annular groove 9^b, thus preventing substantial escape of gases to the top of the fuse on the exterior of the retainer 23 (unless slits 25^c are used). Also 70 edge 24^a of the retainer may make a tight fit with the top of the closure disc 22, thereby preventing escape of gases to the top of the inside of the retainer.

The manufacturer's name, voltage and amperage rating of the fuse, etc., may be placed

by a label or otherwise upon the portion 24 of the retainer. In manipulating the fuse, it is handled only by the insulated grip 9^a and no metal comes in contact with the hands. It will be seen that the construction is very simple and practical, being assembled about a one piece body of molded insulation without the necessity for cement or questionable attachments at any point. 5

In compliance with the patent statutes, I have disclosed the best form in which I have contemplated applying my invention, but it will be realized that many variations may be made within the scope of the claims. 10

What is claimed is:

1. A plug fuse comprising: a one-piece, cup-shaped body of molded insulating material, the body having an annular hand grip adjacent to its upper end and exterior threads adjacent to its lower end, and having within the cavity of the cup formation annularly located closure supporting means; a threaded contact thimble screwed onto the threaded portion of the body; a closure disc entering the cavity of the cup formation and resting against said closure supporting means; and closure retaining means removed from the hand grip portion of the body and located wholly within the space encircled by the hand grip, the closure retaining means being an annular sheet metal member that makes spring contact with the top of the closure disc, 30 and also encircles the closure disc and depends below it to prevent the fuse gases from escaping to the top of the fuse.

2. An annular body for a plug fuse, the body having an open end adjacent to which there are two spaced concentric walls providing an annular channel between the walls, the top of the inner wall being adapted to receive a closure disc and the channel between walls being adapted to receive a closure retainer. 35

3. An annular body for a plug fuse, the body having an open end adjacent to which there are two spaced concentric walls providing an annular channel between the walls, the inner wall having venting passages leading to said annular channel, and the interior surface of the outer wall being recessed to receive a closure retainer. 45

4. A plug fuse body consisting of a single cup-shaped piece of molded insulating material, the body having adjacent to the mouth of the cup formation two spaced concentric walls providing an annular channel between the walls, the exterior of the outer wall being formed as a hand grip, the top of the inner wall being formed to support a closure disc, and the channel between 50 walls being formed to receive a closure retainer. 55

5. A plug fuse body consisting of a single piece of hollow molded insulating material, the body having an open end adjacent to which there are two spaced concentric walls, the top of the inner wall being at a lower level than the top of the outer wall and being provided with venting notches leading to the space between walls, there being additional venting passages leading from the space between walls to the exterior of the 60 body. 65

6. A plug fuse comprising: a body consisting of a single piece of hollow molded insulating material, the body having an open end adjacent to which are two spaced concentric walls, the exterior of the outer wall being formed as a hand grip, and the top of the inner wall being positioned to support a closure disc; a closure disc resting against the top of the inner wall; and a springy closure retainer having an annular flange 70 75

5 overlying the closure disc and having a skirt depending into the space between the concentric walls.

7. For a plug fuse, a closure disc retainer consisting of a spring piece of sheet metal having an inwardly extending annular flange portion to engage the closure disc, and having an annular portion depending from said flange portion, said depending portion comprising two spaced annular walls resiliently connected together.

10 8. A plug fuse comprising: a body having means to support a closure disc and means to interfit with a closure disc retainer; a closure disc supported by the supporting means of the body; and a closure disc retainer securing the closure disc to the body, the retainer consisting of a springy piece of sheet metal having a skirt portion provided with means to make snap engagement with the interfitting means on the body, and having an annular inwardly extending flange portion to re-

15 20 resiliently engage the closure disc.

9. A plug fuse comprising: a body having means to support a closure disc and means to interfit with a closure disc retainer; a closure disc sup-

ported by the supporting means of the body; and a closure disc retainer securing the closure disc to the body, the retainer consisting of a springy piece of sheet metal having a skirt portion provided with means to make snap engagement with the interfitting means on the body, and having an annular inwardly extending flange portion to engage the closure disc, the interior edge of the flange portion being depressed to enable the retainer to yieldingly accommodate 10 manufacturing variations in the thickness of the closure disc.

10. A plug fuse comprising: a body having means to support a closure disc and means to interfit with a closure disc retainer; a closure disc supported by the supporting means of the body; and a closure disc retainer securing the disc to the body, the retainer consisting of a unitary piece of springy sheet metal provided with means to make snap engagement with the interfitting means on the body, and having a portion to resiliently engage the closure disc.
